UNITED STATES PATENT OFFICE.

CHARLES A. GREENE, OF WILMINGTON, CALIFORNIA.

INVALID-LIFTER.

1,299,933.

Specification of Letters Patent.

Patented Apr. 8, 1919.

Application filed October 10, 1918. Serial No. 257,583.

To all whom it may concern:

Be it known that I, CHARLES A. GREENE, a citizen of the United States, residing at Wilmington, in the county of Los Angeles and State of California, have invented new and useful Improvements in Invalid-Lifters, of which the following is a specification.

My invention relates to a lifting device and more particularly to a lifting device 10 for use in hospitals and sick rooms.

In certain physical ailments, patients are extremely sensitive to movement of any kind. The main object of my invention is to provide a lifting and carrying device by 15 means of which a patient or helpless invalid can be handled with the least possible disturbance.

Another object is to provide a lifting device in which bed clothing may be used as 20 a part of a swing or hammock.

Another object is to provide a device by means of which the patient may be held or suspended in any desired position.

Another object is to provide a lifting or 25 suspending device by means of which any member of the body, such as the head, the hand or the foot may be lifted or held in a suspended position.

With these and other objects in view, my 30 invention consists in the construction, combination, and arrangement of parts herein-after shown, described and claimed.

In the accompanying drawings,

Figure 1 is a side elevation of my invalid 35 lifter illustrating its use in lifting an invalid from the bed.

Fig. 2 is an enlarged sectional view on the line 2—2 of Fig. 1, showing the mechanism for suspending the block and tackle 40 to the supporting frame.

Fig. 3 is an enlarged view in elevation of one of the side bars of the lifting device showing the arrangement of the clamps in which the suspending fabric is held to form 45 a hammock or swing.

Fig. 4 is a still further enlarged sectional view on the line 4—4 of Fig. 3 in side elevation of one of the clamps, parts of which are broken away to illustrate the action of 50 the clamping member upon the fabric employed as a sling.

Fig. 5 is a still further enlarged sectional view on the line 5—5 of Fig. 3 showing in greater detail, the construction of one of the 55 clamps.

Referring more particularly to the several

figures, a horizontal bar of channel iron 10 is supported at a convenient height above the floor by uprights 11 and 12 fixed into parallel cross bars 13 and 14 near the floor 60 at right angles to bar 10, and whose ends are equipped with pairs of casters 15 and 16. This constitutes the supporting frame of the lifting device which is made of sufficient length to admit a bedstead lengthwise between the uprights 11 and 12. The horizontal bar 10 extending lengthwise of the frame is composed of barn door channel iron which is fixed with the slot opening 17 downward. A four wheel carriage 70 18 having a flange pulley 19 suspended from its middle point is adapted to run longitudinally from end to end of the supporting member within the channel. This pulley forms a part of a block and tackle combination 20, to the lower block of which a cross bar 21 is fixed. This cross bar extends cross wise of the supporting frame and its ends pass under pivot bars 22 and 23 whose ends are bent and fixed into side bars 24 and 25 75 80 parallel to the pivot bars but longer. The side bars are thus supported in a balanced position and admit of considerable adjustment longitudinally with reference to the cross bar.

U-bolts 26 in which clamps 27 are suspended are fixed into the middle and ends of side bars 24 and 25. The clamps consist of a suspending link 28, an outer clamping stirrup 29 and an inner clamping stirrup 90 30. The suspending link is attached to the inner clamping stirrup at its upper end by a pivot pin 31 through the upturned ends of the stirrup. The sides of the stirrups are pivotally connected by pivots 32 and 33. 95 Washers 34 and 35 are inserted between the inner and outer stirrups to reduce friction. A pin 36 joins the upper ends of the outer stirrups. It is evident that the lower cross bars of the inner and outer stirrups serve 100 as clamping jaws to hold the cloth or fabric passed between them. They are made of strip metal which is set at a slightly oblique angle to the plane of the stirrup. A strip of channel metal 37 is fixed to the outer face 105 of the inner jaw bar and a similar strip 38 is fixed to the inner face of the outer jaw bar. Strips of fiber, hard rubber or the like are inserted in these channels to serve as gripping surfaces to increase the frictional 110 action of the jaws. Fig. 4 clearly shows the clamping action of the jaws upon the fabric

which is formed into a tuft and drawn through between them.

The pivot bars 23 pass through eye bolts 41 which extend through the side bars 25, 5 and serve as supporting bolts to the side bars and at the same time as stops for the cross bar 21.

Operation: When the invalid lifter is to be used the supporting frame with the 10 block and tackle and the cross bar is wheeled into position over the bed as shown in Fig. 1. The side bars are then mounted on the ends of the cross bar and lowered to the proper height by means of the block and 15 tackle which is shifted by means of the carriage 18 until a proper balancing position is found. The edges of the under sheet or blanket are then formed into tufts and drawn between the jaws of the clamping 20 members and the clamps closed to prevent their slipping out. It is evident that the 25 clamps close further and grip the fabric more tightly as the weight on them increases. The hammock or swing thus formed is then raised by means of the block and tackle until the patient is lifted to the desired height above the bed. The patient may be held in this position or carried, if 30 desired, elsewhere by wheeling the device away from the bed.

Other purposes than the one described may be served by my lifter. For instance by using the cloth strip between any two of the clamps, a swing can be produced for lifting or suspending any part of the body. 35 I have shown side bars provided with three clamps. It is evident that two or a larger number might be employed.

Various other changes in construction and arrangement of parts may be made by those 40 skilled in the art without departing from the spirit of my invention as claimed.

I claim:

An invalid lifting and carrying device comprising a supporting frame mounted on 45 casters, said supporting frame having a horizontal and longitudinally extending overhead supporting bar, a block and tackle slidably attached to said horizontal supporting bar, a cross bar fixed at its middle to 50 the lower block of said block and tackle, a pair of horizontal side bars pivotally supported at the ends of said cross bar and adjustable longitudinally with relation thereto, and means for securely gripping and 55 holding the edges of bed clothing and the like suspended between said side bars.

In testimony whereof I have signed my name to this specification.

CHARLES A. GREENE.
